Primary Examiner — Jennifer Rivard*(74) Attorney, Agent, or Firm* — John M. Lipchitz(57) **CLAIM**

The ornamental design for a shaving razor handle, as shown and described.

DESCRIPTION

FIG. 1 is a first perspective view of a design of a shaving razor handle of the present invention;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a second perspective view thereof;

FIG. 9 is a first perspective view of another embodiment of a shaving razor handle of the present invention;

FIG. 10 is a top view thereof;

FIG. 11 is a bottom view thereof;

FIG. 12 is a left side view thereof;

FIG. 13 is a right side view thereof;

FIG. 14 is a front view thereof;

FIG. 15 is a rear view thereof; and,

FIG. 16 is a second perspective view thereof.

The dash broken lines shown illustrate portions of the shaving razor handle and form no part of the claimed design.

1 Claim, 8 Drawing Sheets(56)
